US00D587744S

(12) **United States Design Patent**
Nelson et al.

(10) **Patent No.:** **US D587,744 S**
(45) **Date of Patent:** **** Mar. 3, 2009**

(54) **POINT OF SALE DEVICE**

(75) Inventors: **Eric Nelson**, Waterloo, NE (US); **James Price**, Alpharetta, GA (US); **Hugh McCormack**, Winder, GA (US)

(73) Assignee: **First Data Corporation**, Greenwood Village, CO (US)

(**) Term: **14 Years**

(21) Appl. No.: **29/284,799**

(22) Filed: **Sep. 14, 2007**

(51) **LOC (9) Cl.** **18-01**

(52) **U.S. Cl.** **D18/4.6; D18/4.4**

(58) **Field of Classification Search** ..... D14/336, D14/371, 373-376, 385-387, 399; D18/3.1-3.3, D18/4.1-4.6, 6-8, 11, 12, 12.1-12.3, 19; D21/324, 329, 332, 333; D99/28, 34-36, D99/43; 235/1 E, 2, 7 R, 12, 22, 33, 51, 235/52; 705/12, 15-18, 43

CLAIM

The ornamental design for a point of sale device, as shown and described.

DESCRIPTION

FIG. 1 is a perspective view of a point of sale device, showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines shown in the drawings depict specific functional features and environmental subject matter only, and form no part of the claimed design.

1 Claim, 5 Drawing Sheets
